(57) **CLAIM**

The ornamental design for a coordinate input device, as shown and described.

DESCRIPTION

FIG. 1 is a front-bottom-right perspective view of a first representative embodiment of a coordinate input device according to my new design;

FIG. 2 is a rear-top-left perspective view thereof;

FIG. 3 is a bottom plan view thereof;

FIG. 4 is a top plan view thereof;

FIG. 5 is a left side elevational view thereof, wherein the right side elevational view is a mirror image of the left side elevational view;

FIG. 6 is a front elevational view thereof;

FIG. 7 is a rear elevational view thereof;

FIG. 8 is a front-bottom-right perspective view of a second representative embodiment of a coordinate input device according to my new design;

FIG. 9 is a rear-top-left perspective view thereof;

FIG. 10 is a bottom plan view thereof;

FIG. 11 is a top plan view thereof;

FIG. 12 is a left side elevational view thereof, wherein the right side elevational view is a mirror image of the left side elevational view;

FIG. 13 is a front elevational view thereof;

FIG. 14 is a rear elevational view thereof;

FIG. 15 is a front-bottom-right perspective view of a third representative embodiment of a coordinate input device according to my new design;

FIG. 16 is a rear-top-left perspective view thereof;

FIG. 17 is a bottom plan view thereof;

(Continued)

FIG. 18 is a top plan view thereof;
 FIG. 19 is a left side elevational view thereof, wherein the right side elevational view is a mirror image of the left side elevational view;
 FIG. 20 is a front elevational view thereof;
 FIG. 21 is a rear elevational view thereof;
 FIG. 22 is a front-bottom-right perspective view of a fourth representative embodiment of a coordinate input device according to my new design;
 FIG. 23 is a rear-top-left perspective view thereof;
 FIG. 24 is a bottom plan view thereof;
 FIG. 25 is a top plan view thereof;
 FIG. 26 is a left side elevational view thereof, wherein the right side elevational view is a mirror image of the left side elevational view;
 FIG. 27 is a front elevational view thereof; and,
 FIG. 28 is a rear elevational view thereof.
 The dashed broken lines in the drawings show portions of the coordinate input device that form no part of the claimed design.
